(57) CLAIM

The ornamental design for a patterned neckerchief, as shown and described.

DESCRIPTION

FIG. 1 is a front view of the patterned neckerchief. The squares shown in broken lines indicate the bounds of the detail views provided in FIGS. 2 and 3, and form no part of the claimed design.

FIG. 2 is an enlarged detailed view of the patterned neckerchief, indicated by the broken-line square shown in the lower center of FIG. 1; and,

FIG. 3 is an enlarged detailed view of the patterned neckerchief, indicated by the broken-line square shown in the center of FIG. 1.

1 Claim, 3 Drawing Sheets
